UNITED STATES PATENT OFFICE.

JAMES H. CONNOLLY, OF PAWTUCKET, RHODE ISLAND.

BRAIDING MACHINE.

Application filed October 5, 1922. Serial No. 592,534.

To all whom it may concern:

Be it known that I, JAMES H. CONNOLLY, a citizen of the United States, residing at Pawtucket, in the county of Providence and 5 State of Rhode Island, have invented certain new and useful Improvements in Braiding Machines, of which the following is a specification.

My invention relates to braiding machines 10 and has for its essential objects a more perfect control of the rotation of the bobbin to insure a uniform tension on the yarn; to maintain the carrier in a perfectly vertical position and insure a smooth movement of 15 the carrier base; and to increase the speed of travel of the carrier.

To the above ends essentially my invention consists in such parts and in such combinations of parts as fall within the scope 20 of the appended claims.

In the accompanying drawings which form a part of this specification,

Figure 1 is a side elevation, partially in 25 vertical central section of a carrier embodying my invention as showing the wound yarn or filament in broken lines,

Figure 2, a section on line 2—2 of Figure 1,

Figure 3, a section on line 3—3 of Figure 2,

Figure 4, a section on line 4—4 of Figure 1,

Figure 5, a fragmentary plan view of the 35 guide plate unit, showing carrier guides therein in transverse section, and

Figure 6, a vertical section of the unit on line 6—6 of Figure 5.

Like reference characters indicate like 40 parts throughout the views.

In detail my braider consists of a guide plate unit 10 comprising a center plate 11, quoits 12, and outer plate 13, all arranged in the usual manner to form a pair of sinuous intersecting guide channels 14 extending 45 around the unit having straight portions approaching all crossover points. In detail the plate 11, quoits 12, and plate 13 have marginal or peripheral vertical flanges 17, 18, and 19 respectively extending both above and below the horizontal plane of the 50 web portions of the plates. The flange 18 forms with the web portion 12 of each quoit a nearly annular cavity or recess 21 from which extend passages 22 communicating with curved horizontally disposed grooves 23 in the flange 18 disposed upon opposite

portions of the quoit periphery. The ungrooved portions of each quoit periphery constitute lands 24 at the points of intersection of the guide channels at the crossovers. In the passages 22 are lengths of absorbent material 25 adapted to convey oil from the recess 21 to the guide grooves 23 whereby lubrication is afforded to the carrier bases.

The carrier includes an oblong foot or top plate 30, a bottom plate or base 31 having a depending central lug or stub shaft 32 for engagement with the usual driving members. The foot and base are connected 60 by two spaced posts 33 and 34 in longitudinal alignment with each other. The latter carry intermediate their lengths a guide plate 36. Upon the respective posts both above and below the guide plate 36 are 65 sleeves or bushings 37 and 38 respectively which may be either fixed or rotary, and are removable for wear. The described carrier parts constitute the base of the carrier. In order to facilitate disassembly 70 for replacements the posts usually pass loosely through holes 40 in the plate 36, the bushings are a sliding fit, and the posts provided with threads 42 to engage in threaded 75 perforations 44 in the base. The posts 33 and 34 may be integral with the foot or may be fixed thereto. In this instance they are fastened by dowel pins 46 to the foot, and are integral respectively with the spindle 48 and thread guide post 49, both of 80 which extend through the foot.

The portion of the foot through which the spindle passes is made with an elevation or shoulder 52, while the post 49 extends through a thickened portion or elevation 53. 85 The foot with these elevated portions constitute the body portion of the carrier.

The elevation 52 has a horizontal bore or recess 55 in which is seated a helical spring 56 pressing at one end against the elevation or against a filler plug 57 fast therein, and abutting with its other end against a bolt 58 which presses against an arm 60 pivoted at one end to a screw 61 in the foot. The free end of the arm has an angular lateral 95 head or finger 62.

The spindle 48 has intermediate its length an annular groove 65 adapted to receive an annular indent 66 in a thin metallic rotatable sleeve 67 and retain the latter yieldably against longitudinal movement relatively to the spindle. This construction is 100 105 110

for the purpose of permitting ready withdrawal of the bobbin 75. Fast to or integral with the lower end of the sleeve or tube 67 is a base 69 provided with a depending 5 peripheral flange 70 having vertical equispaced cavities or grooves 71. The base rests upon the elevation 52 or upon a collar 73 upon the spindle and the flange 70 is adapted to enclose and engage the head 62 10 of the member 60. The head naturally registers in the grooves 71 to restrain rotation except during the take off operation, but the portions of the flange between the grooves also have frictional contact with the head 15 and assist in preventing racing of the sleeve and consequent loss of tension. The bobbin 75 has frictional engagement with the sleeve 67 of the bobbin carrier and rotates therewith. The base 77 of the bobbin has radial 20 slots 78 to loosely receive similarly disposed lugs 79 on the disk 69. For the purpose of maintaining the bobbin in axial position on the tube 67 there is fast in the latter, at a point above the spindle, a pin 81 upon which 25 is pivoted the lower end of a spring comprising a vertically disposed shank 83, resilient inclined depending arm 84, and a terminal finger 85. The latter is adapted to press against the end of the bobbin.

30 The thread guide post 49 is rectangular in cross section and has fastened in its upper portion a lateral thread guide 87, and in its upper end a thread guide 88. Slidably mounted on the post 49 is a tension weight 35 comprising a shank 90 and a flange 91. Upon the latter rests a helical spring 93 upon which rests a bearing ring 95 abutting against the thread guide 87. Upon the flange 91 is a thread guide 97 and a lateral projection 98. The projection engages the vertical portion 99 of an angular lever arm having an inclined upper portion 101 and whose horizontal portion 102 is pivoted at its end upon a pin 103 fast in the portion 40 52 of the foot. A finger 105 on the lever portion 102 normally contacts with the arm 60, so that as the weight in its upward travel 45 engages the lever portion 101 the finger 105 compresses the spring 56 and presses the 50 head of the member 60 out of engagement with its groove 71 to release the disk 69.

In operation the carrier bases are impelled through the channels 14 by the usual mechanism acting upon the stub shaft 32. The 55 bushings 37 and 38 run freely in these channels, and together with the enclosed posts 33, 34, and the plates 30, 31, and 36 act to restrain the carrier in an upright and non-swaying position as well as guide the same 60 through the various portions of the channels. The grooves 23 accommodate the guide plate 36 through the curved portions, and this plate draws lubricating oil from the grooves during its travel therethrough. 65 At the straight portions of the channels ad-

jacent the intersections, the sides of the plate 36 slide along the lands 24 and assist in effecting the cross over. To further insure against deviation at the cross overs or intersections the posts 33 and 34 are so spaced as 70 to equal approximately the length of the straight portion of a channel at one side of the point of intersection of two channels. It will be observed that the constituent parts of the bases are replaceable for wear. A 75 less desirable construction of the base is one in which the parts 30, 31, 36, 37 and 38 are an integral whole.

As braiding material is taken to the braiding point of the machine it is led through 80 guides 88, 97 and 87 and thence from the bobbin. Tension is maintained in the braiding material by weight and compression spring 93. The braiding material is led from the bobbin on such side as to normally 85 keep the notched flange 70, and therefore the bobbin, locked against the finger 62. As the braiding material is drawn off to the braiding point the weight rises against the spring 93 and if more material is desired 90 to be taken off than can be provided by slight action of the weight and spring said weight will rise against spring 93 until it moves the inclined upper portion of the 95 lever arm sufficiently to cause the finger 105 to thrust head 62 out of contact with notches in flange 70, thereby releasing the bobbin 75 and permitting it to rotate and cause yarn to be unwound due to tension set up by the 100 weight and spring 93. Immediately as the 105 finger 62 is removed from the notches against the action of spring 55 the latter will thrust the pawl against the smooth inner face of the flange 70, and thereby cause a friction which will restrain flange 70 and consequently the bobbin from too free a rotation, and consequent loss of tension in the 110 thread.

It is intended that all matter contained in the above description or shown in the accompanying drawings shall be interpreted as illustrative and not in a limiting sense.

I claim:—

1. In a braiding machine, a guide plate unit provided with sinuous intersecting 115 channels, and with peripheral grooves opening into the channels, and a carrier base comprising posts slidably mounted in the channels, plates upon the ends of the posts, and a guide plate carried by the posts registering in the grooves.

2. In a braiding machine, a guide plate unit provided with sinuous intersecting 120 channels, and with peripheral grooves opening into the channels, and a carrier base comprising a top plate and a bottom plate engaging exterior portions of the unit, posts spaced from each other in the channels connecting the top and bottom plates, an intermediate plate provided with holes through 125 130

which the posts pass slidably in the grooves, and bushings on the posts between the guide plate and the top and bottom plates.

3. In a braiding machine, a guide plate unit provided with sinuous intersecting channels and with peripheral grooves opening into the channels, and a carrier base comprising posts slidably mounted in the channels, a pair of bushings mounted in each 10 of said posts, and adapted to roll in said channel and a plate connecting said posts and serving as a separator of the individuals of each pair of bushings.

4. In a braiding machine, a guide plate unit provided with sinuous intersecting channels, a carrier base comprising posts slidably mounted in the channels, a pair of rotatable bushings mounted on each side of 15 said posts and adapted to roll in said chan-

nel, a plate connecting said posts and serving to separate the individuals of each pair of bushings, said channels being provided with peripheral grooves opening into the channels to permit clearance for the said plate.

5. In a braiding machine, a guide plate unit provided with sinuous intersecting channels, said guide plate being provided with peripheral grooves opening into said channels, and terminating adjacent the 20 region of intersection, a carrier base comprising posts slidably mounted in said channels, plates upon the ends of the posts, and a guide plate carried by the posts and registering in the grooves.

In testimony whereof I have affixed my signature.

JAMES H. CONNOLLY.
